BLADE MOUNTING STRUCTURE FOR LINOLEUM AND ASPHALT TILE REMOVER

Thomas C. Rush, Mansfield, Mo.

Application January 16, 1950, Serial No. 138,867

2 Claims. (Cl. 262—20)

1

This invention comprises novel and useful improvements in a linoleum and asphalt tile remover and more specifically pertains to an improvement over the similar device set forth in my copending application, Serial No. 63,655, filed December 6, 1948, for Linoleum and Asphalt Tile Remover, now Patent No. 2,520,066, issued August 20, 1950.

The primary objects of this invention are to provide an improved surface scraping device comprising a plurality of circumferentially and axially disposed blades carried by a shaft and rotatable therewith for abrading, scraping or otherwise treating a surface.

Important features of this invention reside in the provision of a surface scraper having a mobile base together with a rotor and an operating means therefor supported upon the base, together with improved constructions of knives carried by the rotor for scraping a surface.

These, together with various ancillary features and objects which will later become apparent as the following description proceeds, are attained by the present invention, preferred embodiments of which have been illustrated by way of example only in the accompanying drawings, wherein:

Figure 1 is a side elevational view, parts being broken away, showing a suitable embodiment in accordance with the principles of this invention;

Figure 2 is a bottom plan view of the mobile supporting base forming a part of the construction of Figure 1 and showing more particularly the vertical adjusting means of the same;

Figure 3 is a diagrammatic view illustrating the radial or circumferentially spaced arrangement of the knives of the rotor of the device;

Figure 4 is a fragmentary end view showing one construction of knife and its arrangement upon the rotor shaft;

Figure 5 is an end elevational view of the arrangement of Figure 4;

Figure 6 is a plan view of the rotor of Figure 1, in accordance with the diagrammatic arrangement of Figure 3;

Figure 7 is a vertical transverse sectional view taken substantially upon the plane indicated by the section line 7—7 of Figure 6;

Figure 8 is a side elevational view of one of the supporting arms and a knife carried thereby;

Figure 9 is a view taken at right angles to Figure 8;

Figure 10 is a view similar to Figure 8 but showing a modified construction of supporting arm and blade;

2

Figure 11 is a view taken at right angles to Figure 10;

Figure 12 is a fragmentary elevational view showing a modified construction for mounting the blades on the rotor shaft showing a different construction of supporting arm and knife blade secured thereon; and

Figure 13 is a vertical transverse sectional view taken substantially upon the plane indicated by the section line 13—13 of Figure 12.

Referring now more specifically to the accompanying drawings, wherein like numerals designate similar parts throughout the various views, attention is directed first to Figures 1 and 2, wherein it will be seen that the numeral 10 represents generally a supporting platform or base which is provided with a customary handle 12 which, in conjunction with a pair of fixed supporting rollers 14 and a vertically adjustable supporting roller 16 render the base mobile as desired.

A suitable prime mover of any desired character indicated at 18, and which may conveniently comprise an electric motor or the like, is provided with a driving belt 20 which serves to impart rotation to a rotor indicated generally by the numeral 22.

At its outer or forward end, the base or platform 10 is provided with a pair of outwardly extending plate-like support brackets 24 which are disposed in vertical parallel relation and which are provided with vertically elongated slots 26 through which extend fastening bolts 28 which serve to vertically adjust and secure in adjusted position journal members 30 of any desired character which are thus mounted upon the adjacent or inner surfaces of the vertical support brackets 24 for vertical adjustment thereon. The above mentioned rotor assembly

40 22 is intended to be journaled in the journal bearings 30 and to be vertically adjustable while extending horizontally between the same in a manner which will be readily apparent. An arcuate guard or shield 32 is pivoted as at 34 at one extremity between the pair of brackets 24 at their inner end, and at its other extremity is adapted to overlie and rest upon the arcuately shaped outer surface of the brackets 24, these arcuated surfaces being indicated at 36. The shield 32 is thus positioned by gravity in the position shown in Figure 1, to thus enclose the upper portion of the rotor 22; but may be pivoted in a clockwise direction about its pivot pins 34 to an open position, whereby access may be had to the upper portion of the rotor assembly.

Referring now more specifically to Figure 2, it

will be seen that the vertically adjustable supporting wheel 16 is journaled upon one extremity of a connecting rod 38, the other end of this connecting rod being slidably received in a bracket 40 which thus serves to slidingly retain the end of the rod 38 to the lower surface of the platform 10.

A pair of supporting brackets or bearings 42 are suitably secured to the bottom surface of the base 10, and rotatably journaled therebetween a crank shaft 44 having a crank throw or crank 46 disposed thus between the bearings 42. By means of a connecting rod cap 48, the connecting rod 38 is secured to the crank throw 46 in such a manner that by rotating the crank shaft 44 through a predetermined angular movement, the angular relation of the connecting rod 37 with respect to the base 10 may be varied whereby the vertical spacing of the supporting wheel 16 with respect to the under surface of the base 10 may likewise be varied to thereby shift or adjust the inclination of the base 10 with respect to the floor or other supporting surface whereby the rotor assembly 22 may be raised or lowered in a manner which will now be readily understood.

This rotor assembly, as shown in Figure 6, preferably comprises an axle or shaft 50 of any desired character which is journaled between and supported between the two journal bearings 30 for rotation about a horizontal axis and for vertical adjustment as above set forth. A plurality of radially extending support arms 52 are rigidly or otherwise secured to the shaft 50 for rotation therewith, and the outer ends of these arms are provided with blades having cutting edges which are adapted to scrape or abrade the surface with which the rotor is to be employed. While it is within the purview of this invention to form these cutting edges integral with the arms 52, it is to be understood that it is preferred to form the same separately and to detachably mount the cutting blades upon the arms in order to obtain the benefits of a superior material for the cutting edges and a more economical material for the supporting arms.

While, as shown in Figures 6 and 7, the supporting arms 52 are provided with beveled edges or the like 54 to constitute the cutting blades, it is preferred to form the blades separate from the arms, as shown in Figures 8 and 9. For this purpose, the blades may consist of flat plates or the like 56 which are provided with elongated slots 58 for the reception of fastening bolts 60 whereby the blades may be separately attached to and adjustably mounted upon the ends of the support arms 52.

Alternatively, instead of the support arm construction disclosed in Figures 6 and 7, the arrangement shown in Figures 10 and 11 may be employed, this consisting of a radially extending arm 62 having a hub portion 64 adapted to be retained by pivot pins in the same manner as at 74 in Figures 4 and 5. The arm 62, at its outer extremity, has an inclined portion 66 which extends backwardly and has an edge 70 which is disposed preferably upon a radius of the hub 64. At the junction of the portion 66 and the arm 62 there is provided an edge 70 which serves as a cutting edge of the blade. In this construction, the center of gravity of the supporting arm and blade unit is offset from the radius extending from the hub to the cutting edge 70, this form of blade being adapted for use in the arrangement of Figure 5.

As shown in Figure 5, the shaft 50 may be

provided with radially disposed pairs of support arms 72, and pivoted between the outer extremities of the arms of each pair as at 74 is a blade assembly which may constitute the construction disclosed and described in connection with Figures 10 and 11. In this event, the center of gravity of the blade assembly of Figures 10 and 11 is offset to one side of the radius joining the center of the hub 64 with the blade edge 70 so that the centrifugal force tends to cause the blade to assume a position from which the same may yield if excessive resistance is encountered by the cutting edge 70 during rotation of the rotor.

Alternatively, the blade construction of Figures 4 and 5 may be employed, the same consisting of a triangular shaped plate 76 having one apex secured to the pivot pin 74, having another apex 78 constituting its cutting edge, and having a third apex 80 disposed to one side of the radius joining the center of the shaft 50 with a cutting edge 78 for the same purpose as set forth in connection with the arrangement of Figures 10 and 11.

Preferably, a multiplicity of blades is provided about the rotor shaft, and it is preferred to form this plurality of blades in an arrangement in which the blades are spaced equidistantly both axially and circumferentially of the rotor shaft. For this purpose, as shown in the diagrammatic view in Figure 3 in conjunction with the showing of Figure 6, this principle of the invention has been illustrated in connection with an assembly consisting of sixteen rotor blades or arms, the same being numbered A-F, respectively. As will be seen from Figure 6, the adjacent blades or arms A through P are disposed consecutively at even axial distances along the rotor shaft, and as shown in Figure 3 are disposed at equal angular intervals about the shaft. However, blades which are adjacent axially of the shaft are preferably disposed in non-adjacent but in regular spaced relation circumferentially of the shaft. Thus, as will be apparent from Figure 3, each blade is disposed at an angular interval with respect to the next axially adjacent blade, which is equivalent to 360° divided by one-half N plus 1, in which N is equal to the number of the blades.

While various other arrangements of the blades could be provided, the foregoing arrangement is particularly advantageous and effective for the purposes intended.

In addition to the foregoing arrangements, the construction of Figures 12 and 13 may be employed. In this construction, the shaft 50 has detachably secured thereon a cylindrical drum 84 provided with a plurality of axially extending, circumferentially spaced slots 82, there being one such slot for each of the intended blades. The drum may be retained as by set screws, not shown, on the shaft 50. A blade-supporting arm or holder 84 in the form of a strip of metallic resilient material has a circular or cylindrical portion 86 which is coiled about the shaft 50 and embraces the same, and is provided with an angulated end portion 88 which is seated in and secured in one of the slots 82. The other extremity of the member 84 has clamped thereon, as by any suitable form of clamp indicated at 90, a plate 90 having a beveled edge 92 and which constitutes the cutting member of the blade. By this arrangement, each of the cutting blades is resiliently mounted and carried by the rotor for rotation therewith.

Referring again to Figure 12, it will be seen that the slots 82 extend from the opposite ends

of the shaft 50, half of the slots extending from one end and half from the other end, the slots in each of the two end sets being spaced at equal circumferential angles, and the slots of the two sets being alternated or staggered with respect to each other. By this means, the coiled and angulated portions of the spring holders may be inserted in the slots from the ends thereof and shoved axially upon the shaft, being retained thereon as by a collar or cap plate 94, which in turn is secured as by fastening screws 96 to thereby lock the cylindrical hubs of the resilient blade holders together in endwise alignment.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having thus disclosed and described the invention, what is claimed as new is as follows:

1. In a surface scraper comprising a support-

ing base and operating means for a rotor, a rotor adapted to be mounted on the base and actuated by the operating means, including a shaft, a drum mounted on said shaft, a plurality of blades mounted on said drum for rotation therewith, said blades being displaced on said drum at equal axial and circumferential intervals with respect to each other, said drum having circumferentially spaced axially extending slots, a plurality of arms, each embracing said drum and having one end anchored in one of said slots, said blades each being mounted on the other end of one of said arms.

2. The combination of claim 1 wherein said arms consist of resilient metal straps.

THOMAS C. RUSH.
